EDWARD C. HANSON AND JOEL SODERHOLM, OF MINNEAPOLIS, MINNESOTA, ASSIGNEES
TO O. B. MCCLINTOCK COMPANY, INCORPORATED, OF MINNEAPOLIS, MINNESOTA, A
CORPORATION OF MINNESOTA

HUMIDIFIER FOR UNIT HEATERS

Application filed June 23, 1930. Serial No. 463,136.

This invention contemplates the provision of a humidifier for unit heaters and the like, the principal object being to provide a humidifier which may be readily attached to heaters now in use and which will function efficiently to moisten the heated air emanating from the heater to the proper degree.

Another object of the invention is to provide a humidifier with a moisture-carrying device of reticulated or open mesh character which supplies the required quantity of liquid for the operation of the humidifier, and which, by reason of its construction, will offer no resistance to the passage of air therethrough.

A further object of the invention is to provide a moisture-carrying device for humidifiers of a reticulated construction, the interstices being sufficiently large to prevent the formation of a liquid film on the device and which will yet supply sufficient liquid for the purposes of the humidifier.

Still another object of the invention is to provide a moisture-carrying device for humidifiers in the form of an endless reticulated fabric or series of spiral springs which may be rotated at any desired speed in front of a heating element, the fabric or springs being supplied with a quantity of liquid.

A further object is to provide a humidifier for heaters which may be associated with the heater at one side thereof while an air-circulating device is provided at the opposite side of the heater to force air through the heater and the humidifier.

Other objects of the invention and the advantages thereof will be more fully brought out as the description proceeds.

In the accompanying drawings we have illustrated a preferred practical embodiment of our invention and two modifications of the construction of the moisture-carrying device. These drawings are submitted by way of example and it is to be understood that we are not limited to the details of construction therein disclosed. It will be apparent to those skilled in the art that the invention is susceptible of embodiment in other forms without sacrificing any of its advantages and

without departing from the scope thereof as defined in the appended claims.

In these drawings:

Fig. 1 is a front elevation of a humidifier constructed in accordance with our invention, certain parts being broken away and other parts shown in section for the purpose of clearness; 55

Fig. 2 is a fragmentary sectional view taken substantially on line 2—2 of Fig. 1; 60

Fig. 3 is a fragmentary view of a spring used in the structure of Fig. 1 as a moisture-carrying device; 65

Fig. 4 is a view in side elevation of the structure shown in Fig. 1, certain parts being broken away and other parts shown in section.

Referring now to the drawings, the reference numeral 10 indicates a suitable casing within which is located a heater 11. This heater may be of any well known and preferred construction and may be heated by any desired heating agent, for example, hot water, steam, and the like. The heater is of the so-called open type construction which is 75 to say that it is formed with spaces between adjacent sections of the heater.

At the rear of the casing we have provided a suitable air-circulating device in the form of a fan 12 which may be operated from any 80 suitable power source, for example, a motor 13. The power unit or motor 13 is conveniently mounted on a bracket 14 secured to the casing 10.

At the front of the heater we have provided 85 a humidifier casing 15 which may be secured to the casing 10 or the heater 11 in any convenient manner. Preferably, and as shown, the front of the casing 15 is open and is provided with a series of louvers or baffles 16. It 90 is to be understood that the casing 15 and the humidifier parts located therein may be supplied as a separate unit readily attachable to heaters now in use.

Within the casing 15 we have provided 95 rollers 17 and 18 suitably journaled in the side walls of the casing at the top and bottom thereof, respectively. These rollers are provided with sprockets 19 and 20 about which is trained a sprocket chain 21. A shaft

22 of the upper roller 17 extends through the casing and is operably connected to a source of power, for example, an electric motor 23. This motor may be of any preferred construction and should be so designed as to rotate the roller 17 at a very slow rate of speed. For this purpose, speed reducing means of any character (not shown) may be associated with the motor.

10 Each of the rollers 17 and 18 is provided with a plurality of grooves 24 in its periphery. A plurality of coil springs 25 are trained about the rollers and rest in the grooves 24. These springs should preferably be made of rust-proof material, for example, bronze, or of other suitable material which is not subject to corrosion by reason of contact with moisture.

20 At the bottom of the casing 15 we have provided a suitable inlet 26 through which water or any other medium to be used as a humidifying agent is introduced into the casing. At the opposite end of the casing 15 we have provided a suitable outlet 27, this being positioned in such a manner as to maintain the level of liquid in the casing practically constant. Further to assist in maintaining the level of liquid constant it will be seen that the inlet opening is considerably smaller than the 25 outlet.

30 As before stated, the moisture carrying devices of the embodiment just described consist of a plurality of coil springs 25. These springs are preferably so constructed that the space between convolutions is relatively large and at least so large as to prevent the formation of a film of liquid between adjacent convolutions. Such a spring when stretched to the proper degree around the two rollers 17 and 18 presents what, in fact, may be termed a reticulated structure. That is to say, the spiral formation of the spring produces, when it is stretched, a series of interconnected narrow elements separated by diagonal interstices.

40 In operation, the rollers 17 and 18 are rotated at a very slow rate of speed, and thus, the coil springs 25 are caused to be immersed in the liquid in the bottom of the casing. As rotation continues, the springs rise out of the liquid and carry with them a certain quantity of moisture. The direction of rotation will, preferably, be counter-clockwise, when the structure is viewed as in Fig. 4 so that the end of the springs which comes out of the liquid will be nearest to the heating element 11. Furthermore, when the fan 12 forces air through the heater 11 and against the springs 50 25 if any drops of water are blown away with the air they will strike against the other side of the springs.

55 Thus, it will be seen that the heating element 11 is positioned between the fan 12 and the humidifier so that the fan 12 will force

air through the heater and then through the humidifier.

60 It will be understood, of course, that the liquid may be supplied to the casing 15 from the water system of the heater 11 where the heater is of the hot water type. When the heater employs some other heating agent the water may be introduced into the casing 15 from any other suitable source.

65 It will be seen from the foregoing that we have provided a humidifier of simple construction which may be readily associated with heaters now in use and that the humidifier will operate efficiently to maintain any desired degree of humidity. By providing a 70 moisture-carrying device of reticulated character, we are enabled to supply to the humidifier any desired quantity of liquid, and yet, the device will offer no resistance to the passage of air therethrough. Moreover, the operation of the humidifier is such as constantly to present in the path of the air current a portion of the moisture-carrying device which has just emerged from the liquid supply.

75 We claim as our invention:

80 1. A humidifier for unit heaters comprising a casing, rollers journaled therein, and a reticulated moisture-carrying device trained about said rollers, said device comprising a plurality of coiled springs.

85 2. A humidifier for unit heaters comprising a casing, rollers journaled therein, grooves in the peripheries of said rollers, and endless springs trained about said rollers and seated in said grooves.

90 3. A humidifier for unit heaters comprising a casing, rollers journaled therein, grooves in the peripheries of said rollers, endless springs trained about said rollers and seated in said grooves, and means for supplying 95 moisture to said springs.

100 In witness whereof, we have hereunto set our hands this 18th day of June, 1930.

EDWARD C. HANSON.
JOEL SODERHOLM.
